UNITED STATES PATENT OFFICE.

FRANK W. MEYER, OF EAST ST. LOUIS, ILLINOIS.

ROTARY ENGINE.

1,267,100.

Specification of Letters Patent. Patented May 21, 1918.

Application filed September 8, 1917. Serial No. 190,340.

To all whom it may concern:

Be it known that I, FRANK W. MEYER, a citizen of the United States, residing at the city of East St. Louis, in the county of St. 5 Clair and State of Illinois, have invented certain new and useful Improvements in Rotary Engines, of which the following is a specification.

The object of this invention is to provide 10 an unusually compact and powerful rotary engine having a stationary crank-shaft, utilizing the cylinders and pistons in lieu of a fly-wheel, having a balanced steam-chest, unusually steam-tight, and with an arrangement whereby the admission of steam to the 15 pistons relieves the main bearings. As a whole, this engine reduces vibration and saves much anchoring.

In the accompanying drawings forming 20 part of this specification and in which like numbers of reference denote like parts wherever they occur,

Figure 1 is an end elevation;

Fig. 2 is a top plan view;

Fig. 3 is a section on the line 3—3 in 25 Fig. 2;

Fig. 4 is a side elevation (partly in section);

Fig. 5 is a section on the line 5—5 in 30 Fig. 4;

Fig. 6 is a view on the line 6—6 in Fig. 4;

Fig. 7 is a perspective view of the 35 interior of the steam-chest;

Fig. 8 is a sectional view of the same on the line 8—8 in Fig. 7;

Fig. 9 is a sectional view on the line 9—9 in Fig. 4; and

Fig. 10 is a fragmental developed detail 40 of steam and oil passages from one port to the other in the steam-chest.

The short cylinder or ring 1 rests upon standards 2. The shaft 3 is rotatable in its bearings and in fixed connection with a rotatable fly-wheel, rotor, or crank-case containing a plurality of piston-rods 5, 6, and 45 7, which are connected to wrist-pins 4 and which respectively reciprocate with pistons 8, 9, and 10 in cylinders 11, 12, and 13 formed in the said crank-case 14. Piston-rod collars 71 encircle crank-shaft 72, and the reciprocation of the said piston-rods rotates fly-wheel or crank-case 14 and thus shaft 3.

A hand-hole 15, closed by hand-hole plate 50 16, allows entrance through ring or cylinder 1 to the cylinders 11, 12, and 13, the bottoms

of which, respectively, are formed by removable plates 17, 18, and 19, which are normally screwed or otherwise suitably fastened so as to close the outer ends of the said 60 cylinders.

Calling the end illustrated in Fig. 1 the front, the front end of cylinder 1 is closed by plate 20 and the rear by plate 21, preferably formed integral with the housing 22. 65 Ball-bearings 23 in race 24 and ball-bearings 25 in race 26 allow shaft 3 to revolve easily, oil being supplied through ports 27. Crank-case 14 is fixed to shaft 3, and pulley 28 is keyed to a reduced part thereof. 70

Passage 30 in the crank-case 14, the end of which is beyond the heads of pistons 8, 9, and 10, allows the admission of steam or other fluid on the outside of the said piston-heads and likewise its exhaust, which permits the engine to run in either direction, this being, furthermore, controlled by the lever 31 and abutment 32, both keyed to shaft 33, journaled in steam inlet box 34 and at 35 in housing 59 in connection with the 75 main body of the engine. When the lever 31 is moved to the right in Fig. 1, the abutment 32 assumes the position shown in dotted lines in Fig. 5 in which the top of abutment 32 is at the right-hand; and movement of lever 31 to the left in Fig. 1 causes abutment 32 to occupy the other position in Fig. 5, in which the top of abutment 32 is at the left.

Inlet of fluid is through pipe 36, and exhaust is through pipe 37. When abutment 32 is in the position in which its top is at the right of Fig. 5, fluid is admitted through pipe 36 to the left-hand side of the chamber in box 34 and passes through pipe 38 to 85 steam-chest 39. When in the opposite position shown by Fig. 5, fluid is admitted to the right-hand part of the said chamber and passes through pipe 40 to steam-chest 39. Thus it will be seen that pipes 38 and 40 90 may either be an exhaust conduit leading from steam-chest 39 to exhaust pipe 37, just as either may be a fluid conduit from inlet 36 to the steam-chest 39. Thus the engine 95 may run in either direction. 100

Bolts 41 attach a housing 59 for steam-chest 39 to plate 20, and bolts 42 attach box 34 to the said housing 59. 105

Gaskets are inserted at all needful points, in order to make the engine steam-tight, and 110 oil-cups or holes are located wherever necessary for suitable lubrication.

Pipes 38 and 40 lead, respectively, to ports 44 and 43—which is the inlet and which is the exhaust depending on the location of abutment 32 relative to inlet 36.

5 Steam-chest 39 is in form a collar containing internal grooves 45, 46, and 47, bounded by ribs 48, 49, 50, and 51 and abutments 52, 53, 54, 55, 56, and 57 and a duplication thereof at the opposite side of the 10 internal periphery of the said steam-chest.

10 A collar 58 fixed to crank-case 14 projects therefrom and is encircled by steam-chest 39 and within which the said collar 58 rotates synchronously with the revolution of 15 crank-case 14 with shaft 3, which is thereby driven.

15 A long strong bolt 60 passes through housing 59, crank-shaft support 61 within the same (which support is longer than the 20 steam-chest 39 is wide), and into the stationary crank 72, thus binding the whole strongly together and supporting crank-shaft 62 in such a way as to allow rotation of crank-case 14. Bolt 60 is encircled by 25 crank-shaft 62, on the end 63 of which the head 64 of bolt 60 is tightly bound, while the longitudinal movement of bolt 60 is limited by screw-threads 65 which engage in crank 72. Outward longitudinal movement 30 of crank-shaft 62 is limited by collar 67, while its outer end is threaded at 68 to receive nut 69. Except at the ends, bolt 60 is of a diameter not to fit tightly the interior of the crank-shaft 62 which as indicated is 35 tubular, thus affording oil passage from any suitable oil-hole or other source of supply.

Piston-rod collars 71 encircle crank-shaft 62, which is eccentric to the axis of rotation of crank-case 14 and shaft 3.

40 Oil-cup 70 supplies oil for packing and lubrication between collar 58 and steam-chest 39, the same flowing through oil-passage 73 into oil-grooves 74, and preventing the escape of fluid from the fluid grooves 45, 46, 45 and 47.

45 The convenience and simplicity of the arrangement side by side of the piston-rod collars 71 on crank-shaft 62 will be observed, the center one being provided with a straight 50 connection to its piston while the others are bent, so to speak, to make a straight connection with their respective pistons. In lieu of this arrangement the crank-case can be made of suitable size and the cylinders staggered.

55 Any number of cylinders may be used, and the three herein shown and described are merely by way of preference or illustration.

60 Pipes 38 and 40 lead to opposite sides of the steam-chest 39, and fluid from one of them, *e. g.*, pipe 38, enters through port 44 one of the grooves 46 and extends to the abutments 53 and to the similar abutment at the opposite end of the said groove, and 65 through passage 66 to grooves 45 and 47, and

when rotation of fly-wheel or crank-case 14 has caused registration of the end of port 30 in collar 58 with the said groove 46, steam passes through port 30 into the outer end of its cylinder and forces the piston downwardly to the extreme of its travel, at which time port 30 comes into registration with the opposite groove 46 in steam-chest 39, and exhausts through port 43 and pipe 40 into box 34 and thence through exhaust- 75 pipe 37.

75 When reversal of direction of operation of the engine is desired, lever 31 is shifted as hereinabove described in connection with Fig. 5, and at the time of so doing stud 76, 80 threadedly connected at 77 in the end 75 of oil-passage 73, throws steam-chest 39 around to its opposite position, slot 78 allowing this movement of stud 76.

80 Steam-passages or bores 79 allow the passage of steam from the groove 46 on one side of the abutment to the other side of the said abutment, thus balancing the valve or steam-chest 39 by preventing binding.

85 Since the constant flow of oil from oil-feed 70 through passage 73 and oil-grooves 74 will produce an accumulation in the housing of crank-case 14, an opening 80 in ring 1 allows its removal by withdrawing plug 81, or instead of plug 81 a pipe may connect 95 with opening 80 and lead away the surplus oil to any suitable tank or pump for resupply to oil-feed 70.

90 There is a port 30 for each of the cylinders 11, 12, and 13, each capable of use alternately 100 for inlet and exhaust.

95 The weight of the member 14, particularly because of the added weight due to the cylinders 11, 12, and 13 and because they are located near its periphery, enables the 105 same to serve as a fly-wheel, as well as a case containing the crank, crank-shaft, and related members.

100 The operation of the machine is as follows:

105 The steam is turned on in pipe 36, lever 32 is moved from the full-line position of Fig. 5 to the dotted line position at the right thereof in Fig. 5; steam passes through pipe 38 to port 44 and into that groove 46 110 adjacent to pipe 38; thence when a port 30 registers with groove 46 into one of the cylinders, thus driving the piston for that cylinder outwardly. Due to the push of the crank-shaft 62 upon each piston, the same 115 is pushed inwardly again into its respective cylinder, ready for a fresh outward impulse of steam through port 30. By the time steam from port 30 has pushed a piston to the extreme of its outward movement, its 120 port 30 has come into registration with the other groove 46 that is in communication with port 43 and pipe 40, while another port 30 (leading to another cylinder) has come into registration with the opposite or 125 130

inlet groove 46. If the direction of operation of the engine be reversed, as hereinabove described, the function of the various inlet and exhaust members is merely reversed. The action of the crank-shaft 62 on the pistons 8, 9, and 10 causes the rotation of fly-wheel or crank-case 14 and with it collar 58 and shaft 3, the bearings for which are relieved by the fact that the succession of cylinders in the said fly-wheel or crank-case 14 are balanced by the reception and exit of steam by the fact that the steam inlet is toward the axis of rotation of the said crank-case 14, collar 58, and shaft 3.

15 Although steam has been herein mentioned as the motive power, yet other fluid, such, for instance, as air or water, may be used.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a rotary engine, the combination of a rotary cylinder-containing member having a plurality of cylinders, with pistons and piston-rods therein and a collar in fixed connection therewith and projecting laterally therefrom, said collar and the wall of each of said cylinders having a steam-passage therethrough, a collar encompassing the first-mentioned collar, adapted to act as a valve in connection with the rotation of said fly-wheel and its attached collar, means for delivering steam to said valve-collar and exhausting steam therefrom, said collar having grooves with abutments therein also bores leading from the grooves on one side of abutments to those on the other, said grooves receiving steam from said valve-collar and delivering it into said bores for balancing the valve or steam-chest by preventing a binding action at that point, a crank-shaft with which the said piston-rods are connected, a housing within which the said fly-wheel is adapted to revolve, a power-shaft in fixed connection to the said fly-wheel, a stationary crank within the said housing and mounted on the inner end of the said power-shaft and supporting the inner end of the said crank-shaft, and a support within the said valve-collar for the outer end thereof.
2. In a rotary engine, the combination of a rotary cylinder-containing member having

a plurality of cylinders, pistons, and piston-rods therein and a collar in fixed connection therewith and projecting from one side thereof, there being a steam-passage through the said collar and the wall of each of the said cylinders, a collar encircling the said first-mentioned collar and adapted to act as a valve in connection with the rotation of said fly-wheel and its attached collar, means for admitting steam to the said valve-collar and exhausting therefrom, there being grooves with abutments within the said collar, and bores leading from the grooves on one side of abutments to those on the other, said grooves receiving steam from said valve collar and delivering it into said bores for balancing the valve or steam chest by preventing a binding action at that point.

3. In a rotary engine, the combination of a rotary cylinder-containing member having a plurality of cylinders, pistons, and piston-rods therein and a collar in fixed connection therewith and projecting from one side thereof, there being a steam-passage through the said collar and the wall of each of the said cylinders, a collar encircling the said first-mentioned collar and adapted to act as a valve in connection with the rotation of said fly-wheel and its attached collar, means for admitting steam to the said valve-collar and exhausting therefrom, there being grooves with abutments within said collar and bores leading from grooves on one side of abutments to those on the other, said grooves receiving steam from said valve-collar and delivering it into bores for balancing the valve or steam-chest by preventing a binding action at that point, a crank-shaft with which the said piston-rods are connected, a housing within which the said fly-wheel is adapted to revolve, a power-shaft in fixed connection to the said fly-wheel, a stationary crank within the said housing and mounted on the inner end of the said power-shaft and supporting the inner end of the said crank-shaft, and a support within the said valve-collar for the outer end thereof.

In testimony whereof I hereunto affix my signature.

FRANK W. MEYER.
